[57] ABSTRACT

The dashpot timer of this invention includes a substantially cylindrical glass tube in which travels a piston having a diameter slightly less than that of the interior of the tube. A gas defines the medium in the cylinder in which the piston containing a sharp edge orifice is adapted to travel. The flow generated in the cylinder is predominately an inertial flow through the sharp edge orifice with the shear flow and pressure flow between the piston and cylinder being relatively insignificant. The device of the present invention operates in the inertial flow region whereby the viscosity effects are relatively small compared with the inertial effects of the fluid.

SHARP EDGE ORIFICE DASHPOT TIMER

The subject invention relates to a gas sharp edge orifice dashpot which utilizes the clearance between an axisymmetric piston and an interior cylindrical wall as the seal between the piston moving relatively to the cylinder and containing a sharp edge orifice through which the gas is metered.

Annular orifice dashpots utilizing air as the metering fluid are known in the art and are described in U.S. Pat. No. 3,171,245. Such air dashpots are finding wide acceptance for certain time delays having certain functions of the applied force or where the available force is within certain narrow limits. Applications where the applied force is sufficiently small usually being less than a few ounces and requiring complete temperature insensitivity or where it is desired to have the time delay vary with the inverse square root of the applied force, or both, air timers heretofore unavailable and unrealized are necessary. For such cases the gas sharp edge orifice dashpot timer of this invention has been found to be eminently satisfactory and acceptable and capable of yielding time delays ranging from a few milliseconds to several minutes and more.

An understanding of the particular nature of the flow past a piston as it descends along the wall of a cylinder and through a sharp edge orifice in the piston is important in determining the predictability and accuracy of the rate of descent. The type of gas flow that the present invention utilizes is generally termed inertial flow through the orifice and creeping, shear or pressure flow between the piston and cylinder which involves very slow gas motion between the piston and cylinder, that is, motion at very low Reynolds numbers and in which viscous forces are predominant over inertial forces whereas the opposite is the case for the flow through the sharp edge orifice in the piston where the gas velocity is large yielding large Reynolds numbers and thus the inertial forces predominate over the viscous forces. The size of the orifice and piston-cylinder clearance is such that the dominant portion of the flow occurs through the sharp edge orifice with the small clearance between the piston and cylinder thus acting as a seal.

It is, therefore, an object of the present invention to provide a gas sharp edge orifice dashpot which eliminates the disadvantages, limitations and drawbacks of the prior art devices and which is exceptionally reliable, susceptible to long life and relatively inexpensive to manufacture.

The gas dashpot of the subject invention has been successfully utilized as a bomb retardation sensor system. In this application, the dashpot piston is acted upon by the deceleration force due to the parachute retarding the bomb and the piston mass. Since this force varies with the square of the bomb velocity and since the flow through the sharp edge orifice varies as the square root of the applied force, the flow varies as the first power of the bomb velocity. This gives an approximate constant safe separation distance between the bomb and the plane when the bomb becomes armed, for the case where the bomb is released from a level flight. Although several approaches may be taken to seal the gas in the cylinder, the present invention proposes to seal the gas through the use of ends either made as an integral part of the cylinder or cemented on. Thus, the dashpot of the subject invention can be stored for long periods of time without the danger of changes in the density of the gas.

Other objects and advantages will become apparent from the following detailed description which is to be taken in conjunction with the accompanying drawings illustrating an exemplary preferred embodiment of the invention and in which:

FIG. 1 is a diagrammatic perspective view of a dashpot timer incorporating the teachings of this invention utilizing a piston containing the sharp edge orifice the initial and terminal position of which for the prescribed time delay being shown in dotted lines;

FIG. 2 is an enlarged fragmentary longitudinal sectional view of this dashpot showing the internally disposed piston traveling through the selected gas to an applied force;

FIG. 3 is an enlarged fragmentary sectional view of the piston showing the sharp edge orifice in detail; and,

FIG. 4 is a longitudinal sectional view illustrating the dashpot timer applied to a bomb retardation sensor.

Referring now to FIGS. 1 to 3, a dashpot timer of this invention will include an outer cylinder 2 having a contained gas 4 therein through which a piston is adapted to travel under an applied force F. The piston also defines with the inner surface of the cylinder's relatively small annular clearance through which a small portion of the gas passes. The major portion of the fluid passes through the sharp edge orifice 8.

Referring now to FIG. 4, a bomb retardation sensor is shown generally at 10. In order to seal the gas 12 in the cylinder 14, plates 16 and 18 are integrally formed with or securely cemented to cylinder 14.

Upon release of the bomb and deployment of its drag chute, the retardation subjects the piston 20 to a deceleration causing it to begin traveling against a spring 22 at a rate determined by the flow of the gas 1 through the sharp edge orifice 23. When the piston reaches end 24 it bridges contacts 26 and remains in this position due to end 18 which is magnetic. Prior to bomb release the piston 20 was held against end 16 by bias spring 22 where contacts 32 were bridged. Thus, the distance which the piston 20 has traveled along its axis provides a convenient measure of elapsed time and varies as the square root of the applied force. Through the use of additional circuitry the piston can be utilized to trigger various devices such as an arming mechanism 40 of a bomb.

The motion of the piston in the cylinder depends upon the equation of inertial fluid flow through a sharp edge orifice providing the flow in the clearance between the piston and cylinder can be neglected. This relationship is:

$$Q = K \sqrt{2\Delta P/\rho} A$$

where:

55 Q = volume flow rate in.³/sec.

K = experimental constant (usually about 0.7)

ΔP = pressure drop across the orifice

ρ = density of gas

A = area of the orifice

60 This equation holds for large Reynolds' numbers where the viscous effects can be neglected.

The time delay for a given piston travel can be found from the relationships

$$dx/dt = Q/A'$$

$$\Delta P = F/A'$$

solving

$$dx/dt = K/A' \sqrt{2F/\rho A' A}$$

or if the force is independent of time

$$t = \int_0^L \frac{dx}{\frac{KA}{A'} \sqrt{\frac{2F}{\rho A' A}}}$$

where:

L = length of piston travel

t = time delay

F = applied force

A' = area of piston cross section

Since the viscosity does not appear in this equation, the time delay will be independent of the viscosity insofar as the assumptions made above hold. That is, the Reynolds' number must be much larger than 1, and the fluid flow between the piston and cylinder must be negligible. For a particular design air has functioned well from -65° to 160° F with a force of 0.047 lbs. on the piston.

For most devices contemplated, the radius would be less than about one-half inch. The pressure could vary from about 0.1 psi to several hundred psi, however, for most applications the pressure drop across the orifice would probably not exceed 20 psi. The clearance would probably never exceed 0.001".

For most applications, however, no temperature compensation would be necessary.

The fact that the time delay is proportional to the square root of the applied force makes this timer ideal for application for constant distance arming for rockets. For this case only one end of the cylinder would be sealed.

The cylinder 14 is preferably made from glass or other ceramic material, since precision glass tubes are readily available. However, other materials could also be utilized. Similarly, the end plates 16 and 18 could be made from glass, ceramic or metal such as aluminum. The plates may be integrally formed with the cylinder or may be bonded to the ends of the cylinder.

In summary, the present invention accomplishes and contributes the following advantages to the dashpot timer are:

1. Time delay as function of the square root of the applied force:

For all other fluid dashpots, the time delay will follow some other function of applied force. To achieve constant safe separation distance arming for retarded bombs, the time delay must vary as the inverse square root of the applied force. This is accomplished through the inertial flow equation for a sharp edge orifice.

2. Temperature compensation: The viscosity of gases change by a factor of 1.5 over the temperature range -65° to $+160^\circ$ F. Even over a very limited temperature range, the viscosity changes several percent. Consequently, if accuracy is to be achieved even over limited temperature ranges the Reynolds number for the flow through the sharp edge orifice must be large compared to 1.

3. Piston rates: For most of the devices of the present invention, the rate of travel of the piston will be on the order of 0.005 to 50 inches per second. The most im-

portant range effectively satisfied by this invention is the 0.1 to 25 inches per sec. area.

4. Sealing: The second major reason why gas dashpots have failed in military applications has been the inability to seal the gas when a rod or other member must emerge from the timer. With the use of an electrical output there is no sealing problem and a constant density of the gas can be maintained.

5. Military applications: Based on present knowledge, no gas inertial flow gas dashpot has been successfully applied to a military fuze in the past. Other applications and other than one-time use dashpot timer applications may be found in the above identified patent.

6. Piston cylinder seal: Based on present knowledge, no inertial flow gas dashpots have been made wherein the clearance between the piston and cylinder is the seal. Where orifice-type dashpots have been utilized in the past, in a piston-cylinder configuration, "O" rings or similar type seals have been used or viscous flow has been used.

Although a preferred embodiment of this invention has been described and illustrated herein, it should be understood that this invention is in no sense limited thereby but its scope is to be determined by that of the appended claims.

I claim:

1. A gas, sharp edge orifice dashpot timer comprising:

30 a cylinder having a substantially cylindrical interior wall;
a piston disposed in said cylinder and having an outer diameter slightly less than the diameter of said interior wall and containing a sharp edge orifice whereby the major portion of dashpot gas flow occurs through the sharp edge orifice;
a gas in the cylinder through which the piston is adapted to move with the relative flow of the gas being inertial flow through the orifice and flow in lubrication region between the piston and cylinder, which involves Reynolds' numbers much larger than 1 in the orifice so that the viscous effects can be neglected for flow through the orifice and the inertial forces dominates.

45 2. The invention in accordance with claim 1 wherein the Reynolds number for flow through the orifice is greater than 100.

3. The invention in accordance with claim 1 wherein means are provided to adapt the timer to a bomb for use as a retardation sensor.

50 4. The invention in accordance with claim 1 wherein means are provided to adapt the timer for use as a rocket arming delay timer.

55 5. The invention in accordance with claim 1 wherein the piston is substantially cylindrical and the piston rate of travel through the gas being defined by the following equation:

$$dx/dt = KA/A' \sqrt{2F/\rho A'}$$

60 when the flow in the clearance is neglected, where K is an experimental constant, F is the axial force applied to the piston, ρ is the density of the gas, A is the area of the orifice, A' is the piston cross section area, and dx/dt is the velocity of the piston.

65 6. The invention in accordance with claim 5 wherein the radius of the piston is less than about 1/2 inch.

7. The invention in accordance with claim 5 wherein F/A' is of a value of about 0.05 psi to several hundred psi.

8. The invention in accordance with claim 5 wherein h , the piston-cylinder clearance, is less than 0.001

5

inches.

9. The invention in accordance with claim 5 wherein the gas is air.
